William D. Richards

UNITED STATES PATENT OFFICE.

ISAIAH N. ZELLER, OF CHICAGO, ILLINOIS.

PICTURE FRAME, BUTTON, BADGE, AND THE LIKE.

1,418,222.

Specification of Letters Patent. Patented May 30, 1922.

Application filed April 29, 1919. Serial No. 293,456.

To all whom it may concern:

Be it known that I, ISAIAH N. ZELLER, a citizen of the United States, residing at Chicago, county of Cook, and State of Illinois, have invented certain new and useful Improvements in Picture Frames, Buttons, Badges; and the like, of which the following is a specification.

This invention relates to improvements in picture frames, buttons, badges or the like, which may be adapted to display photographs, pictures, designs, advertising matter, mottoes, or the like, and having means by which they may be readily attached to, or removed from, articles such, for example as clothing.

One of the principal objects of the invention is to produce a frame or button, which is easily engageable with, or detachable from, ordinary articles of clothing, and which may be so manipulated as to remain fixedly in position, thereby averting inadvertent loss.

A further object is to provide such a frame or button with a transparent outer covering, with a metallic shell back of said covering said shell having its central portion cut away so that a photograph, picture, or other design may be placed behind said shell and be displayed through and be protected by said outer covering.

A still further object is to provide a frame or button comprising few simple and cheaply constructed parts, so designed as to afford a sufficient holding means, and which is of neat and attractive appearance.

A still further object is to produce a frame or button so formed that the photograph, picture, or design may be easily changed if necessary or desired.

These and other objects are attained by the novel construction and combination of parts hereinafter described and shown in the accompanying drawings which form a material part of this disclosure, and in which:

Figure 1 is a rear plan view showing a frame or button made in accordance with the invention;

50 Figure 2 is a front or face view of the same.

Figure 3 is a vertical sectional view taken on the center line of a modified form of frame or button.

Figure 4 is a plan view showing the combined re-enforcing and spring means of the pin; 55

Figure 5 is another front view showing a further form of construction;

Figure 6 is a rear view of the same, parts 60 being broken away in order to disclose the structure; and

Figure 7 is a transverse sectional view taken on line 7-7 of Figure 6.

Referring to the drawings, the frame or 65 button will be seen to be comprised of a face or front portion 10, which is of transparent material, such as celluloid, or the like, having its flanged edges 11 folded or turned re-entrantly so as to produce a 70 casing having a rounded periphery 12 and enclosing an annular space 14, which extends completely around adjacent to the periphery of the frame or button, within the casing 75

Within the said casing is a thin metal shell 15, which is similarly shaped, and fits the casing closely. The central portion 16 of the shell 15 is cut away to form an aperture therein of some suitable design such, 80 for instance, as round, oval, heart shaped, or star shaped, the shell being adapted to receive and hold a photograph, picture, design or advertisement, or display card, indicated at 17, which will be visible through the 85 aperture in the shell and the transparent face 10 of the front casing.

Engageable within the space 14, and formed to fit closely within the interior of the rounded edges, is a partial ring 18, 90 formed of resilient wire, one of its ends 19, being positioned substantially 120 degrees from the other end 20, which is bent to form an arm 21 at a substantially right angle, which extends radially toward the center of 95 the curved element 18, the arm being formed with either a curved portion or a short helical coil 22, from which extends a tongue or pin 23, bent slightly on the center 24, the continuing part 25 terminating in an acute 100 pin point 26, the length of which is such as to extend nearly or quite to the opposite portion of the resilient element 18.

In assembling the engaging element within the shell and casing, the ends of the spring 105 curved element 18 are pressed toward each other until said element enters within the opening 28, formed between the inner edges

of the open back of the frame or button and seats itself in the annular space 14, enclosed by the flanged edges 11, the point of the pin being inserted through the slot 29 to be 5 come seated in the recess 14 behind said flanged edge.

The material of which the spring element 18 is made is adapted to force the same strongly outward, but permitting it to be 10 rotated within the recess 14 so that the point 26 may when required, be brought into register with the slot 29, formed through the flanged edge 11, permitting the button to be removed.

15 In operation, the button is rotated laterally until the point 26 clears the slot 29, when engagement may be made with the textile material of the garment upon which it is to be used, and the point 26 is then 20 re-entered into the slot and the button again rotated whereupon the pin will come into the position shown in Figure 1, and become firmly secured in the garment.

In the adaptation shown in Figure 3, a loop 25 30 is formed substantially central of the pin bar, the loop being adapted to receive and engage with a pin or transverse bar 31 thrust through the supporting material and said loop in known manner.

30 In the adaptation shown in Figures 5 to 7 inclusive the same general structure is observable, except that at one point of the flange 11 the material is extending to form a flat surface 33, terminating at one edge in 35 a slot 34, while at the opposite end is an outwardly turned pocket 35, adapted to receive and contain the pin point 36, the opposite end of which has a coil 37, integrally connected with the end 20 of the curved 40 spring element 18.

In this adaptation it is obviously necessary in operation to spring the pin bar out from the pocket 35, into the space 14, and out of the slot 34, whereupon engagement may be 45 made with the clothing and the pin returned to the pocket for security.

Obviously the face 10, may be ornamented or bear any desired design, and it will be apparent that the act of securing or releasing the pin is of a simple nature, while the button, as a whole, is firmly secured when in an attached position.

The coils 22 and 37 act as springs, and serve to make the pins more resilient in action than they would otherwise be, it being understood that the pin is bent to project angularly outward from the plane of the curved member 18, to facilitate engagement and disengagement of the pin with the cloth 60 and also that when said pin is pressed through the slot 29 into the annular space

14, it will bear firmly against the flange 11 to hold the parts in place.

It will be obvious that any desired photograph, picture, design, or advertisement, 65 properly shaped to fit within the metal shell 15, may be introduced or forced through the opening 28 in the back of the frame or button, and that the same will be held in place therein by the flanged edges 11, and the 70 engaging elements. Also that such photograph, picture, design, or advertisement will be plainly visible through the central aperture 16 in the metal shell, and the transparent casing. 75

It will also be obvious that the engaging element to hold the inserted card in the frame is not necessarily limited to a pin structure but that various forms of engaging elements such for instance as an annular 80 ring could be used in the case of a picture frame or mirror.

Having thus described my invention and set forth the manner of its construction, what I claim as new, and desire to secure by 85 Letters Patent is:—

1. A button or like article comprising a rigid shell having an opening on its face adapted to display a picture card placed behind it, the outer edge of said shell being 90 turned backward to form an annular rim to hold said card in position, a transparent material permanently secured over said rim and covering the outer surface of said shell and means adapted to detachably seat within 95 said rim and engage said card whereby different cards may be interchangeably received within said button without removing said transparent material.

2. A button or like article comprising a 100 rigid shell having an opening on its face adapted to display a picture card placed behind it the outer edge of said shell being turned backward to form an annular rim to hold said card in position, a transparent 105 material permanently secured over said rim and covering the outer surface of said shell and means comprising a pin bar adapted to detachably seat within said rim and engage said card whereby different cards may be 110 received within said button without removing said transparent material and said pin bar also adapted to secure the button to a garment or the like.

In testimony whereof, I have signed my 115 name to this specification in the presence of a subscribing witness, this 4th day of March, 1919.

ISAIAH N. ZELLER.

Witness:

M. A. KIDDIE.
